UNITED STATES PATENT OFFICE

JAMES HARRIS GRIFFIN, OF ST. HELENS, ENGLAND, ASSIGNOR TO PILKINGTON BROTHERS LIMITED, OF LIVERPOOL, ENGLAND, A LIMITED LIABILITY COMPANY OF GREAT BRITAIN

DRAW-OFF CONTROL DEVICE FOR LIQUIDS

Application filed March 14, 1931, Serial No. 522,594, and in Great Britain March 21, 1930.

This invention relates to draw-off control devices for liquids which have to be continually agitated such as those containing solid matter in suspension and has for its object an improved draw-off control device which does not become clogged by solid or coagulated matter.

According to the invention an air jet in the body of the device is directed against the passage leading from the liquid supply pipe towards the discharge orifice and operates to prevent the flow of liquid through the said passage and at the same time keeps the passage free of solid or coagulated matter.

The drawings shown in section, in Figures 1 and 2, two alternative forms of draw-off control devices for liquids made according to the invention and attached to a liquid supply pipe 1.

The same reference figures apply to like or corresponding parts represented in Figures 1 and 2. A passage 2 in the valve body 3 leads the liquid from the supply pipe 1 toward the discharge orifice 4. A pipe 5, connected with a supply of air under pressure, terminates within the valve body 3 in a nozzle 6 which is directed toward the passage 2.

Accumulation of solid matter in the supply pipe 1 is prevented by maintaining the liquid therein in circulation.

The jet of air issuing from nozzle 6 prevents the flow of liquid from the supply pipe 1 into the passage 2 and keeps the passage free of any accumulation of solid matter.

On stopping the supply of air to the nozzle 6, the liquid is free to flow through the passage 2 and out of the discharge orifice 4, these parts being so constructed that there is no passage in which the liquid can remain stationary.

Having described my invention, I declare that what I claim and desire to secure by Letters Patent is:—

1. In a draw-off control device for liquids the combination of a supply pipe in which the liquid is adapted to be maintained in circulation, a discharge passage therefrom and a nozzle directed toward the discharge

end of the passage, the flow of liquid from said discharge passage adapted to be prevented by a jet of air flowing from said nozzle.

2. In a draw-off control device for liquids the combination of a supply pipe in which the liquid is adapted to be maintained in circulation, a discharge passage therefrom and a nozzle aligned with the discharge passage to direct an air jet against the surface of the liquid in the discharge passage.

3. In a draw-off control device for liquids the combination of a supply pipe in which the liquid is adapted to be maintained in circulation, a discharge passage therefrom, a chamber into which said discharge passage leads, a nozzle aligned with the discharge passage and opening into said chamber, and an outlet from said chamber open to atmosphere.

In testimony whereof I have affixed my signature hereto.

JAMES HARRIS GRIFFIN.
